UNITED STATES PATENT OFFICE.

WILLIAM D. LEWIS, OF PLYMOUTH, PENNSYLVANIA.

CAN-OPENER.

SPECIFICATION forming part of Letters Patent No. 289,919, dated December 11, 1883.

Application filed, August 31, 1883. (No model.)

To all whom it may concern:

Be it known that I, WILLIAM D. LEWIS, a subject of the Queen of Great Britain, at present residing at Plymouth, in the county of 5 Luzerne and State of Pennsylvania, have invented certain new and useful Improvements in Combined Can-Openers and Knife-Sharpener; and I do hereby declare the following to be 10 a full, clear, and exact description of the invention, such as will enable others skilled in the art to which it appertains to make and use the same, reference being had to the accompanying drawings, and to letters or figures of 15 reference marked thereon, which form a part of this specification, and in which—

Figure 1 is a side view; Fig. 2, a top view; Fig. 3, a detail.

My invention relates to certain improvements in combined can-openers and knife-sharpeners, whereby I am enabled to produce 20 a compact and efficient can-opener and knife-sharpener, and which can be manufactured so cheaply as to become a household article, the arrangement of the various parts of which 25 I will now proceed to describe.

Referring to the drawings, similar letters of reference indicate like parts.

A represents the wooden handle; B, the shank; C, the double-edged knife-blade or 30 cutter.

e is a pin secured to one side of the knife-blade, upon which pin is mounted a grooved roller, E, which, when the can-opener is in use, engages with the edge of the can and guides 35 the knife-blade or cutter the proper distance from the rim. It also acts as a fulcrum for the knife or cutter.

F are legs secured to the shank B, upon which legs the can-opener rests when not in use.

G and G' are knife-sharpeners, secured to the shank B by the bolts H and thumb-nuts H'. Said knife-sharpeners are made of highly-tempered cast-steel, and are formed in two parts, g and g'. These parts are adjustable to and from 45 each other by means of the bolts H and nuts H', and the slots g² (shown in Fig. 3) in said parts g and g'. By this arrangement different edges can be put on knives, as desired. The sharpener G is provided with teeth i, and is 50 used for sharpening knives when they are very dull. The other sharpener, G', has no teeth, and is used to finish off and put a fine edge on the knife.

Having thus fully described my invention, I 55 claim as new and desire to secure by Letters Patent—

1. The can-opener having the handle A, shank B, cutter C, and grooved roller E, secured to one side of said cutter, substantially as and for the purpose shown and described.

2. The combined can-opener and knife-sharpener, consisting of the handle A, shank B, legs F, the cutter C, having the grooved roller E, and the knife-sharpeners G and G', 65 composed of the parts g and g', substantially as shown and described.

In testimony whereof I affix my signature in presence of two witnesses.

WILLIAM D. LEWIS.
